UNITED STATES PATENT OFFICE

96,166

DESIGN FOR A GRAVE VAULT

Frank H. Endres, Milwaukee, Wis.

Application April 13, 1935, Serial No. 56,359

Term of patent 14 years

To all whom it may concern:

Be it known that I, Frank H. Endres, a citizen of the United States, residing at Milwaukee, in the county of Milwaukee and State of Wisconsin, have invented a new, original, and ornamental Design for a Grave Vault, of which the following is a specification, reference being had to the accompanying drawing, forming a part thereof.

The single figure of the drawing is a perspective view of a grave vault showing my new design.

I claim:

The ornamental design for a grave vault, substantially as shown.

In witness whereof, I hereunto subscribe my name this 26th day of March, 1935.

FRANK H. ENDRES.
